UNITED STATES PATENT OFFICE.

JAMES N. PARRAHM, OF DENVER, COLORADO, ASSIGNOR OF ONE-HALF TO JOHN MCKINSTRY, OF DENVER, COLORADO.

SHADE AND CURTAIN HANGER.

1,078,162.

Specification of Letters Patent. Patented Nov. 11, 1913.

Application filed November 1, 1912. Serial No. 728,983.

To all whom it may concern:

Be it known that I, JAMES N. PARRAHM, a citizen of the United States, residing at Denver, in the county of Denver and State 5 of Colorado, have invented certain new and useful Improvements in Shade and Curtain Hangers, of which the following is a specification.

My invention relates to shade and curtain hangers for windows and its object 10 resides in the provision of a simple device which is constructed to be secured to the upright members of a window casing by clamping engagement with the edges thereof and which when applied in a pair at the 15 upper end of the casing is capable of supporting both a curtain pole and a shade roller in their proper positions with relation to the window.

With the above object in view my invention 20 comprises a clamping element which is adjustable to adapt it for use on window casings of different widths and a reversible bracket which is constructed to support 25 the ends of the shade roller and a curtain pole at either side of the window and which is adjustably connected with the clamping element to allow regulation of the distance between the two brackets of a 30 pair of the devices after they have been applied to the casing, to correspond with the width of the shade and the curtain to be suspended therefrom.

An embodiment of my invention has been 35 shown in the accompanying drawings in the various views of which like parts are similarly designated and in which,

Figure 1 represents the upper portion of a window casing with a pair of my improved hangers in their operative position together with a shade roller and a curtain pole which are suspended from the brackets included in their construction. Fig. 2, a transverse section through one of the 40 upright members of a window casing showing a top view of one of the hangers as applied thereto, and the end portions of a curtain pole and a shade roller which are supported on the pair of hangers as shown in Fig. 1. Fig. 3, a longitudinal section 45 through one of the hangers. Fig. 4, an enlarged section taken along the line 4-4, Fig. 3. Fig. 5, a face view of the hanger, look- 50 ing in the direction of the arrow *a*, Fig. 3. Fig. 6, a rear view of the hanger, looking 55 in the direction of the arrow *c*, Fig. 3, and Fig. 7, a face view of the clamping element comprised in the invention in the position shown in Fig. 5, with the bracket element 60 removed.

Referring more specifically to the drawings, the reference characters *A* designate the upright members of a window casing, *B* the hangers which, as shown in Fig. 1, are applied in a pair at the upper portions 65 thereof, and *C* and *D* respectively, the shade roller and the curtain pole which are supported on the hangers. Each of the hangers comprised in the pair is composed of a clamping element and a therewith adjustably connected bracket element from which the curtain pole and the shade roller are suspended, and both hangers of the pair are of similar construction with the exception 70 that in one, the position of the bracket on the clamping element is reversed with relation to the relative positions of the corresponding parts on the other.

The clamping element consists of two members 5 and 6 which are composed of 75 plates of equal and uniform width and which at one of their ends are bent at right-angles to provide the jaws 7 and 8 which by engagement with the edges of the upright members of the window casing, secure the 80 hangers thereto. The jaw 7 on the member 6 has a pair of inturned prongs 9 which enter into the wood at the edge of the casing to more firmly secure the hanger thereto, and the jaw 8 of the member 5 is provided with a threaded aperture for the reception of a set-screw 10 which engages the 85 upright member *A* at its opposite edge. The two members of the clamp are adjustable to any one of a number of positions to 90 adapt it for use on casings of different widths and with this end in view, the member 6 is provided with a number of longitudinal slots 11 of equal length and the other member 5 has at its end, opposite to the jaw 9, a transverse bar 12 which is integrally connected therewith by means of a short, centrally disposed neck 13. When the members of the clamp are in their co-operative positions, the plates of which they 95 are composed overlap one another in longi-

tudinal alinement and the neck 13 at the end of the one extends loosely through one of the slots 11 in the other. The two members are held in their relative positions by 5 means of a band 14 composed of a strip the ends of which are bent inwardly to embrace the longitudinal edges of the plates of the two members as well as those of the corresponding part of the bracket - element, as 10 will hereinafter be more fully described, and the inner member 6 has in its longitudinal edges, opposite notches 15 which are adapted to provide passages for the bent ends of the band 14, when the members are 15 being disconnected or assembled.

The bracket element consists of a longitudinally slotted plate 16 which in width corresponds with the plates of the clamp members and which at one of its ends is bent at 20 right-angles to provide the support 17 from which the curtain pole and the shade-holder are suspended. The support 17 has at its extremity, two, reversely curved, resilient arms 18 which are adapted to receive the 25 curtain pole between them, their resilience allowing their adjustment to accommodate poles of different diameter. The support 17 is further provided at opposite points in its upper and lower edges, with reversely slanting notches 19 which at their inner ends have circular enlargements to adapt them for the reception of either the flat or the 30 round end of the spindle which forms part of a spring-actuated shade roller. It will be understood that the object of providing 35 two notches at opposite points in the edges of the bracket is to render the latter suitable for use at either side of the window casing. The slot 20 in the body - portion of the 40 bracket is of a width adapted to receive the neck 13 on the member 5 of the clamping element, the length of the said neck being such as to admit the said body portion as well as the plate of the slotted clamp member 45 between the inner edge of the bar 12 and the thereto opposite surface of the member of which it forms part.

When the parts are assembled, the plate 16 of the bracket is placed upon the outer 50 surface of the outer member of the clamp with the neck 13 extending through its longitudinal slot 20 as hereinbefore explained and the band 14 is placed around the three plates to maintain them in their relative positions. When the parts are thus assembled, the bracket element may be moved longitudinally to any desired position within the limits determined by the engagement of the 55 ends of its slot with the neck, and the distance between the supporting parts of the 60 brackets on the two hangers of the pair may thus be regulated in accordance with the widths of the shade and the curtain to be suspended therefrom. To adjust the distance 65 between the jaws of the clamping ele-

ment, the two members of which it is composed are disconnected by sliding the band until its ends register with the notches 15 in the member 5 and then turning the latter through a quadrant arc to allow the bar 12 70 to pass through the slot of the member 6 through which its neck was inserted. The members are subsequently reassembled by passing the bar through another one of the slots in the member 6 and turning the member of which it forms part to its normal position in alinement with the other member and with its notches in register with the in-turned ends of the band which subsequently is moved to a point remote from said notches 75 to maintain the members in their adjusted 80 position.

The bracket element is applied to the clamping element by inserting the bar 12 through its slot 20, turning the same through 85 a quadrant arc until it is alined with the plates of the clamp-members, and then sliding its end into the band 14.

Having thus described my invention, what I claim and desire to secure by Letters- 90 Patent is:

1. A hanger of the class described comprising an element adapted to be rigidly attached to a window-casing, and a bracket adapted for the support of a curtain-pole 95 and a shade-roller, reversibly secured upon the said element.

2. A hanger of the class described comprising a clamping element, and a bracket secured thereto, the said element being composed of two lapping, longitudinally alined, plates bent at their outer ends to provide opposite jaws, one of said plates having a longitudinal slot and the other plate having at its inner end, a transverse bar connected therewith by a neck which is adapted to be inserted through said slot, and a band embracing said plates and composed of a strip whose ends are bent inwardly, one of said plates having notches for the passage of 105 said ends.

3. A hanger of the class described comprising a clamping element composed of two lapping, longitudinally alined plates bent at their outer ends to provide opposite jaws, 115 one of said plates having a longitudinal slot, and the other plate having at its inner end, a transverse bar integrally connected therewith by a neck which is adapted to be inserted through said slot, a bracket including a slotted plate disposed between said bar and the outer surface of the slotted plate of said element, and a band embracing the plates of the said element and of the said bracket.

4. A hanger of the class described comprising an element adapted to be rigidly attached to a window casing, and a bracket connected with said element and composed of a body portion and an end-portion bent 120

125

130

at an angle thereto and having at its end, two reversely curved, resilient arms adapted to receive a curtain pole between them.

5. A hanger of the class described comprising an element adapted to be rigidly attached to a window casing, and a bracket connected with said element and composed of a body portion and an end-portion bent at an angle thereto and having at its end, 10 two reversely curved, resilient arms adapted

to receive a curtain pole between them, and in its upper edge, a slot to receive an end of the spindle of a curtain roller.

In testimony whereof I have affixed my signature in presence of two witnesses.
